Edgar Dale & Co.

UNITED STATES PATENT OFFICE.

ALBERT S. MOSHEIM, OF EAST ORANGE, NEW JERSEY.

POWDER-PUFF.

1,357,412.

Specification of Letters Patent.

Patented Nov. 2, 1920.

Application filed November 29, 1919. Serial No. 341,403.

To all whom it may concern:

Be it known that I, ALBERT S. MOSHEIM, a citizen of the United States, and residing at East Orange, in the county of Essex and State of New Jersey, have invented certain new and useful Improvements in Powder-Puffs, of which the following is a specification, such as will enable those skilled in the art to which it appertains to make and use the same.

This invention relates to the manufacture of what are known as powder puffs and particularly to two-faced powder puffs, and the object of the invention is to provide a device or devices of the class described which is strong and durable, sanitary in use, and which may be washed or cleaned whenever desired; and with this and other objects in view the invention consists in a powder puff of the class specified which is constructed as hereinafter described and claimed.

The invention described and claimed herein is what I call the reinforced rubber-set powder puff in which rubber or other adhesive material is used for the purpose of securing the separate puff bodies together, and said rubber or adhesive material is reinforced by fibrous or other material embedded therein, and the invention constituting the subject-matter of this application covers divisional matter of a prior application filed by me April 5, 1919, Ser. No. 287,674, and is fully disclosed in the following specification, of which the accompanying drawing forms a part, in which the separate parts of my improvement are designated by suitable reference characters in each of the views, and in which:—

Figure 1 is a side view of a complete powder puff made according to my invention, with part of the construction broken away and in section;

Figs. 2, 3 and 4 are detail views showing the separate steps in the method of making the puff; and

Fig. 5 an enlarged detail view of a part of the construction employed.

In Fig. 1 of the drawing I have shown at 10 a complete powder puff and in the manufacture of said puff a large number of wool, cotton or silk fabric strands 12 cut to the desired length as shown in Fig. 2 are passed into and held in a suitable sleeve-like holder 13, in a compact and compressed form. The compressed fabric strands 12 as shown in Fig. 2 form one of the body parts of the

puff and in securing two of these body parts together, I first apply to one face of said body parts a coating of adhesive material 14 in a liquid or plastic state, the adhesive material being preferably rubber. This adhesive material is applied when the fibrous bodies are in their compressed state within the sleeve 13 as shown in Fig. 3.

In making up the puff shown in Fig. 1, two fabric strand bodies 15 treated in the manner shown in Fig. 3 are placed together, or the faces of said bodies to which the adhesive material is applied are brought together. In this operation a reinforcing member 16 preferably composed of a sheet of fibrous material is placed between the abutting faces of the fabric strand bodies 15 in the manner shown in Fig. 4, and in this operation the opposite end portions 17 of a ribbon or band 18 are also placed between the member 16 and one of the fabric bodies 15. With the parts in the position shown in Fig. 4, the separate bodies 15 are brought together under slight pressure, while the adhesive material 14 is still in its plastic state, and these bodies are held together for a sufficient time to insure the proper connection of said bodies.

On the completion of the above operations a complete powder puff such as that shown at 10 in Fig. 1 will be produced, and this puff consists of two puff faces 19 and 20 joined by a central strip of adhesive material 21, preferably rubber, and this strip 21 is reinforced or strengthened by the reinforcing member or sheet 16. Upon removing the sleeves 13 from the fabric strand bodies 15 in the method of making the device it will be apparent that said bodies, or the strands thereof, will be free and allowed to extend outwardly thus producing around the periphery of the puff 10 a neat and finished edge as shown at 22 in Fig. 1, which will normally conceal the sheet 21 of the adhesive material as well as the reinforcing sheet 16.

In my improved method of making two-faced powder puffs and securing the separate faces 10 and 20 together by the sheet 21 of adhesive material, preferably rubber, the separate strands 23 of the bodies 15, or the inner ends thereof, are set in the sheet 21 as clearly illustrated in Fig. 5. It will, therefore, be seen that when rubber is employed in the sheet 21 I produce a rubber-set two-faced powder puff, and by embedding the reinforcing sheet 16 in the sheet 21,

the possibility of tearing the sheet 21 is obviated, the sanitary qualities of the puff retained and the washing or cleansing thereof whenever desired made possible.

5 Having fully described my invention, what I claim as new and desire to secure by Letters Patent, is:—

- 10 1. A two-faced powder puff of the class described comprising two similar body portions, each of which is composed of a plurality of fabric strands, an intermediate sheet composed of adhesive material to the opposite faces of which the separate fabric strands of said bodies are secured and a 15 reinforcing sheet embedded in said intermediate sheet.
- 15 2. A two-faced powder puff of the class

described comprising two similar body portions, each of which is composed of a plurality of fabric strands the adjacent faces of 20 said bodies being secured together by a sheet of rubberized material to the opposite side faces of which the separate strands of the body portion are secured, and a fabric reinforcing sheet embedded in said sheet of 25 rubberized material.

In testimony that I claim the foregoing as my invention I have signed my name in presence of the subscribing witnesses this 17th day of November 1919.

ALBERT S. MOSHEIM.
